SURFACE VAPORIZER WITH WATER REPELLING VAPORIZATION SURFACE

BACKGROUND OF THE INVENTION

1. Field of the Invention

The invention relates to the field of inhalation narcotic devices.

2. Description of the Prior Art

In inhalation anesthesia there have been used to an increasing extent as the anesthetic or narcotic, halogenated hydrocarbons and ether, which afford, in addition to good narcosis properties, above all, the advantage of being neither combustible nor explodable.

These materials are vaporized, in the main, in special vaporizers which are arranged in the fresh gas inlet of the inhalation equipment. The fresh gas, which consists mostly of oxygen or of nitrous oxide-oxygen mixtures, is withdrawn from pressurized bottles of the gas and, consequently, it is practically free of water vapor.

If, on the other hand, one wishes to vaporize these halogenated inhalation narcotics inside of the anesthetic circulation system by means of so-called surface or wick vaporizers, as is customarily done with diethylether, then the active vaporization surfaces are inactivated at once by being coated with liquid water, since the halogenated substances are specifically heavier than water. In addition, there have been used as the wick materials in such surface vaporizers gauzes made of natural or synthetic fibers which have no specific water repelling properties. The vaporization of the halogenated narcotic agents in the narcotic circulation system may also be object to, however, for another reason. During the continuous circulation of the gases an uncontrollable increase of the concentration of the gases can arise which can lead to an overdosage of the narcotic which is dangerous to the patient. Because of this, such vaporizers may find use only in combination with a metering device for each specific narcotic.

SUMMARY OF THE INVENTION

The object of the present invention is to provide means for the use of surface vaporizers within the narcotic circulation system of inhalation narcotic devices so that the surfaces do not become deactivated by films of water.

The essence of the present invention resides in the use of vaporization surfaces and elements, in inhalation narcotic devices, which are made of synthetic resins which have water repellent properties.

BRIEF DESCRIPTION OF THE DRAWING

The drawing shows, in section, a vaporizer which contains an embodiment of the present invention.

DESCRIPTION OF THE PREFERRED EMBODIMENT

The device described below is based on the idea, according to the present invention, that the conventional fibrous bodies which have been used as wicks in the prior art surface, or wick vaporizers, are replaced by porous members made of synthetic plastics, which, due to their chemical structure will absorb the narcotics which are to be vaporized but which will repel liquid water. Synthetic substances of this type include, mainly, halogenated polymers of the aliphatic hydrocarbon series, and preferably, polymers made of fluorinated and perfluorinated monomers such as polytetrafluoroethylene (known commer-

cially as Teflon resin).

Thus, in accordance with the present invention, by suitable shaping of the active vaporization surfaces and elements it is provided that the water is deposited on such surfaces in beads and flows therefrom, but not, however, so as to flow into the storage container for the liquid narcotic. The placement of the vaporizer inside the narcotic circulation system is so arranged that the circulation system is provided with threaded couplings, which do not match any of the parts of the usual narcosis devices with the exception of the threaded joints of the narcotic metering device and special reducers or connectors of the narcosis device.

The devices of the present invention may be further explained by reference to the drawing which shows, in section, a narcotic vaporizer. The vaporizer is fastened to other elements of the narcotic circulation system by means of screw or threaded members 1 and 2. The narcotic metering device is screwed into the internally threaded member 1. On the externally threaded member 2 there may be screwed different junction members for accomodating different types of narcosis devices, as for example, cones of different diameters or special threaded joints.

The vaporizer housing is divided into two concentrically running inner chambers 3 and 4. Lower chamber 3 serves as a storage container for the liquid narcotic which is transported into upper vaporization chamber 4 by means of capillary force through several concentrically arranged porous rods 5 which are made of one of the water repellent synthetic resin materials referred to above.

Also, in order to increase the active vaporization surface of chamber 4, at least a portion of the surface is coated with a porous coating 6 of the same type of water repellent synthetic resin as is used for rod 5.

The known way of arranging flaps or valves for the selective or partial partitioning of the flow of gas through the vaporizer are only shown in general and not in detail. Thus, a regulatable gas current dividing flap 7, which is rotatable on an axle 8, may be so used as to either allow the gas stream 10 entering from below to pass through the vaporization chamber 4 unhindered, as is shown in the drawing by the arrows depicting the flow of such gas stream, or the flap can be used to divert a portion of the gas stream through vaporization chamber 4 and allow the remainder of the stream to pass through the vaporizer without entering the vaporization chamber. The regulating screw which is accessible from the outside of the vaporizer and which is used for the operation of a gas flow partitioning device is not shown.

In order to render the filling level of the narcotic in storage chamber 3 visible, the chamber is enclosed by an annular glass cylinder 9.

Filling connections, drainage connections, as well as ventilator canals for the narcotic storage chamber are also not shown.

I claim:

1. In a surface vaporizer for a narcotic circulation system comprising a narcotic liquid supply chamber, a vaporizing chamber having active vaporizing surfaces, and porous liquid transfer members extending between the supply chamber and the vaporizing chamber, the improvement in which said surfaces and members consist of a porous synthetic resin polymer of a perfluorinated olefin having water repellent properties.

2. In a vaporizer as in claim 1, in which said olefin is tetrafluoroethylene.
